George Breed
BY *Charles N. Butler*
ATTORNEY.

UNITED STATES PATENT OFFICE.

GEORGE BREED, OF PHILADELPHIA, PENNSYLVANIA, ASSIGNOR TO LYRACHORD COMPANY, OF NEW YORK, N. Y., A CORPORATION OF NEW YORK.

ELECTRIC SWITCH.

1,164,984.

Specification of Letters Patent. Patented Dec. 21, 1915.

Application filed March 15, 1912. Serial No. 683,944.

To all whom it may concern:

Be it known that I, GEORGE BREED, a citizen of the United States, residing in the city of Philadelphia, county of Philadelphia, and 5 State of Pennsylvania, have invented certain Improvements in Electric Switches, of which the following is a specification.

My invention relates to electric switches having resilient blades and its primary object is to provide improved means for effecting the desired electrical separation and mechanical connection of such blades.

My improved means, in their preferred form, comprise the combination with the 15 switch blades of a pliable or yielding insulating material (such as blotting paper) for insulating them, and a device such as a metal band, clip or keeper for clamping the blades and insulating material together in firm re- 20 lation.

The characteristic features of my improvements are fully disclosed in the following description and the accompanying drawings in illustration thereof.

25 In the drawings, Figure 1 is a perspective view of a switch embodying my improvements; Fig. 2 is an enlarged transverse sectional view of the same; Fig. 3 is an enlarged longitudinal sectional view thereof; 30 Fig. 4 is a top plan view of a modified form of switch embodying my improvements; and Fig. 5 is a longitudinal sectional view of the construction shown in Fig. 4.

As illustrated in Figs. 1, 2, and 3, the 35 switch comprises the angular metal base 1; the resilient metal strips 2, 3, and 4; the layers of pliable material 5, 6, and 7 alternating with the blades, which are insulated thereby, and the metal band or keeper 8 which is 40 tightly drawn around the blades and insulating layers to a connection with the base, suitably made by soldering the ends 8' thereto, the several parts being thereby firmly fixed together. The pliable insulating strips 45 are, as shown, of greater width than the blades, which are embedded therein and normally separated thereby, the blades being engaged in succession by pressure applied to the blade 4.

As shown in Figs. 4 and 5, the switch comprises the metal base 10 having the hook 10' with the insulation 11 connected thereto by the clip 12, in combination with the resilient blades 13, 14, 15, 16, 17, 18, and 19, which are insulated by the pliable layers 20, 21, 22, 23, 24, 25, 26, and 27. A band or keeper 28 is drawn tightly and secured around the blades and insulation so as to bind them together and embed the blades in the pliable layers. The blades are adapted to be electrically connected in succession, in the reverse order of the numerals applied thereto, by the application of pressure to the blade 19, the latter and the blades 17 and 18 being normally held by their resiliency in engagement with the insulation 11.

While the blotting paper specified has been found an entirely satisfactory insulating material of the pliable character described, other materials may be used, such as asbestos, soft rubber, soft skins and various woven fabrics. Such insulating materials may be protected from the absorption of moisture by saturating them with oil, if circumstances shall render this desirable; or when such material has been combined in the switch it may be coated with shellac or other suitable substance adapted for protecting it.

Having described my invention, I claim:

1. A switch comprising a plurality of blades, compressible insulating material alternating with said blades, said blades being embedded in and insulated by said material, and means for binding said blades and material together.

2. A switch comprising a plurality of blades, compressible insulating material alternating with and surrounding said blades, and binding means for holding said blades and material together.

In witness whereof I have hereunto set my name this 13th day of March, 1912, in the presence of the subscribing witnesses.

GEORGE BREED.
